UNITED STATES PATENT OFFICE.

WILLIAM SEYMOUR, JR., JAMES O. GROFF, AND ALBERT SCHAAF, OF CHICAGO, ILLINOIS, ASSIGNORS TO JOSEPH T. RYERSON & SON, INC., OF CHICAGO, ILLINOIS, A CORPORATION OF ILLINOIS.

METAL-BENDING MACHINE.

Application filed April 2, 1925. Serial No. 20,216.

This invention relates to improvements in metal bending machines particularly adapted for use in bending sheet metal and wire mesh, and more particularly relates to 5 such a machine designed for use in bending woven wire mesh to form trough-like or U-shaped members, commonly known to the building trade as stirrups, and which are adapted for use in the construction of concrete buildings to be imbedded in heavy 10 floor beams, and the like, to provide a reinforcing means therefor.

In the erection of fireproof buildings, which are usually constructed of steel and 15 concrete, it is desirable that means be provided for reinforcing the concrete and especially the concrete supporting beams for the flooring of such buildings. Steel bars or members are therefore arranged in the concrete 20 molds and are usually supported therein by means of U-shaped supporting members or stirrups which are usually arranged and supported in the mold in such a manner that the longitudinal reinforcing bars, 25 supported by the stirrups, will be positioned in the lower portion of the beam when the concrete has been poured and the molds removed.

The particular object of this invention is 30 to provide a machine for bending or forming such stirrups which are preferably constructed of woven wire mesh consisting of a plurality of heavy wires or runners connected together in spaced relation by means of a 35 plurality of comparatively lighter wires which are usually welded or otherwise secured to the heavy supporting wires at their points of contact.

A further object of the invention is to 40 provide such a machine of simple and inexpensive construction, adapted for manual operation to bend and form from woven wire mesh, such stirrups, the machine also being provided with suitable adjustments 45 whereby stirrups of various sizes may be made.

The object of the invention therefore is to provide an improved stirrup bending machine.

50 Other objects of the invention will appear from the following description and the ac-

companying drawings and will be pointed out in the annexed claims.

In the drawings there has been disclosed a structure designed to carry out the various 55 objects of the invention, but it is to be understood that the invention is not confined to the exact features shown as various changes may be made within the scope of the claims which follow.

60 In the accompanying drawings forming part of this specification,

Figure 1 is a longitudinal sectional view of the improved stirrup bending machine showing the movable die in raised inoperative position;

Figure 2 is a side elevation of the machine showing the movable die in lowered or operative position;

Figure 3 is a rear end elevation of the 70 machine;

Figure 4 is a cross sectional view on the line 4—4 of Figure 2;

Figure 5 is a cross sectional view on the line 5—5 of Figure 2 showing the means for 75 clamping the movable die against the work;

Figure 6 is a front end elevation of the machine with the operating mechanism at the opposite end of the device omitted;

Figure 7 is a cross sectional view on the 80 line 7—7 of Figure 2 showing a piece of wire mesh positioned between the fixed and movable jaws and also showing one of the forming angles actuated to upwardly and inwardly bend the ends of the heavy wires;

85 Figures 8 and 9 are similar figures showing the various steps in completing the formation of the stirrups;

Figure 10 is a sectional plan view on the line 10—10 of Figure 1;

90 Figure 11 is a perspective view of a completed stirrup;

Figure 12 is a detail sectional view of a portion of a concrete floor and the supporting beams therefor showing the stirrups positioned in the beams.

95 The novel stirrup bending machine shown in the accompanying drawings preferably comprises a lower supporting fixed jaw or member 15 which preferably is T-shaped in cross section as shown in Figures 7, 8 and 9. This supporting jaw is preferably supported

by means of suitable legs 16 having their upper ends secured to the vertical web thereof by bolts 17. These legs are preferably outwardly inclined, as shown in Figures 6 and 7, and have their lower end-portions outwardly bent to provide feet 18 which are preferably apertured so that the machine may be suitably anchored to the floor. The upper horizontal portion of the jaw 15 provides a surface upon which the work or wire mesh is placed during the bending operation.

A jaw 19 is movably mounted above the fixed jaw 15. This movable jaw is also preferably T-shaped in cross section and has a forming plate 21 demountably secured to the lower face thereof as shown in Figures 7, 8 and 9. The width of the forming plate 21 is determined by the size of the stirrup to be formed, and this plate therefore is demountable so that various sizes of forming plates may be employed. The jaw 19 is preferably reinforced by means of strips or bars 22 mounted, one on each side of the vertical web thereof and secured thereto by suitable means such as bolts or rivets 20.

The means provided for actuating the forming plate 21 is shown in Figures 1, 2, 3, 4, 5 and 6. The weight of the jaw 19 and the forming plate 21 is counteracted by means of a counterweight 23 suspended from an arm 24 which has its opposite end pivotally connected to the central portion of the plate holder by means of a link 25, clearly shown in Figures 1 and 2. The arm 24 is mounted on a pivot 26 carried by the upright standards 27 which are secured to the frame of the machine as particularly shown in Figure 3. The machine frame preferably comprises a pair of spaced plates 28 which are mounted upon and secured to the opposed supporting legs 29. Referring particularly to Figure 10, it will be noted that the horizontal flanges at the rear end of the fixed jaw 15 have been cut away so as to leave only the vertical web of the jaw, the upper edge of which will be flush with the upper bearing surface of the jaw. To each side of this vertical web section of the jaw 15, a filler block 31 is secured by means of the angle plates 32 which have their vertical web-sections bearing against the filler blocks as clearly shown in Figure 4. The vertical web section of the jaw 15, filler blocks 31 and the vertical webs of the angle plates 32 are then interposed between the upright frame plates 28 and the parts securely clamped together by the bolts 33 which pass through the frame plates 28, angle plates 32, filler blocks 31 and the vertical web of the jaw 15 as shown in Figure 4. The frame plates 28 preferably have a portion thereof cut away as shown in Figure 2 so that the horizontal flanges or webs of the angle plates 32 may be seated

on the frame plates as shown in Figure 4. The above described construction therefore provides a very rugged and substantial frame construction for supporting the main operating mechanism of the machine.

Angle bars or irons 34 are preferably secured to the upper portion of the plates 28 to provide a supporting means for one end of a plurality of rods or bolts 35 having their upper ends secured thereto and their lower ends secured to the horizontal webs of the angle plates 32. These rods or bolts provide vertical guides for the movable jaw 19 as will subsequently be described. Referring to Figure 3, it will also be noted that the upright standards 27 are mounted upon the angle bars 34 and are secured thereto by the upper ends of a pair of the guide rods 35 (see Figure 2). The rear end portion of the jaw 19 is preferably provided with an offset 36, which offset is formed by cutting away the lower horizontal web of the bar as shown in Figure 1. It will also be noted in this figure that the reinforcing bars or plates 22 on each side of the jaw 19 preferably extend to the end of the jaw. Angle plates 37 are mounted on the opposite sides of the reinforcing plates 22 and are secured thereto by means of bolts 38 passing through the entire structure as clearly shown in Figure 4. The angle plates 37 are preferably of the same length as the angle plates 32 secured to the frame of the machine. The lower horizontal webs of the angle plates 37 are apertured to receive the lower ends of a plurality of bushings 39 which have their lower ends secured thereto, which bushings form vertical guides for the jaw 19 and therefore the forming plate 21 secured thereto. Suitable compression springs 41 have their ends connected to the horizontal webs of the angle plates 37 and the angle bars 34 and function to upwardly lift the end of the plate holder to the position shown in Figure 1.

The means provided for downwardly forcing the jaw 19 and therefore the forming plate against the wire mesh or work resides in the provision of an eccentric or cam 42 which is mounted directly above the jaw 19 between the two frame plates 28 and is supported upon and actuated by a shaft 43 journaled in the upper portion of the plates 28. A cam block 44 is preferably secured to the upper edge of the jaw 19 and the reinforcing bars 22 to provide a bearing surface for the face of the cam or eccentric when the jaw is being downwardly forced against the wire mesh. One end of the shaft 43 outwardly extends on one side of the machine and has an operating arm 45 secured thereto to which one end of a suitable cable 46 is secured. This cable preferably passes around a sheave 47

mounted on the machine frame and thence to the opposite end of the machine where it is secured to an operating lever 48 which may be mounted on the floor, as shown, or be secured to the machine frame. When the lever 48 is moved from the position shown in Figure 1 to that shown in Figure 2, the jaw will be downwardly forced against the lower supporting plate, thereby securely 10 clamping the work between the forming plate and the fixed jaw. When the operator releases his grip on the lever 48, the action of the weight 23 and also the springs 41 will tend to upwardly lift the jaw 19 and the forming plate to the position shown 15 in Figure 1.

As a result of the forming plate 21 being of considerable length it is desirable that means be provided at the opposite end thereof whereby such end may also be downwardly forced against the work to securely clamp it against the fixed jaw 15. Such means preferably consists of a clamping means which is pivotally mounted on the 25 end of the T-shaped jaw 15 adjacent the operator's end of the machine. This clamping means preferably comprises a forked member 51 which has its lower end pivotally connected to the end of the jaw 15 by means 30 of a pin 52. A block 53 is slidably mounted in the forked end of the member 51 and is retained therebetween by means of a guide pin 54 which passes through the block 53 and has its ends slidably mounted in slots 35 55 provided in the forked end of the member 51. A cap 56 is secured to the upper end of the member 51 and has mounted in threaded engagement therein, a clamping screw 57 which has its lower end rotatably connected to the clamping block 53. By 40 means of this novel device it will readily be seen that when the clamp is moved from the position in Figure 1 to that shown in Figures 2 and 5, the ends of the jaw 19, and 45 also the reinforcing strips 22 secured thereto, will be interposed between the forks of the clamping member 51 so that when the clamping screw 57 is downwardly rotated in its bearing in the cap 56, the clamping block 53 will be securely clamped against the jaw 19 to downwardly force it against the wire mesh positioned upon the fixed jaw 15. To release the movable jaw, the clamping 50 screw 57 will be rotated in the opposite direction until the clamp may be oscillated on its pivot 52 and moved out of engagement with the jaw 19 to the position shown in Figure 1. It is to be understood of course that the horizontal web of the jaw 19 is cut away at the end thereof so as to provide clearance for the clamp when in the position shown in Figure 2.

The means provided for bending the work 55 or wire mesh after having been clamped between the forming plate and the main fixed

jaw 15 of the machine frame preferably consists in the provision of a pair of forming angles 58 which are pivotally and adjustably mounted on each side of the machine in spaced parallel relation to the T-shaped 70 jaw 15. As particularly shown in Figures 7, 8, and 9, the forming angles 58 are preferably secured to the supporting plates 59 which preferably have their ends pivotally mounted in angle brackets 61 and 62 as 75 shown in Figure 10. Pivot pins or studs 63 are provided for thus pivotally supporting the forming angles 58 and the supporting plates 59, and these studs, as will be seen by reference to Figure 10, preferably have 80 their ends secured to the end plates 64 of each supporting plate 59 while the body of the studs 63 are rotatably mounted in apertures 65 provided in the angle brackets 61 and 62. A plurality of apertures 65 are 85 preferably provided in the brackets 61 and 62 so as to provide means whereby the forming angles 58 may readily be adjusted to and from one another for the purpose of adjusting them to the width of the forming plate used. By this novel method of mounting the forming angles 58 it will readily be seen that the distance between the two angles, which is determined by the width of 90 the forming plate 21 and therefore the width of 95 the stirrup to be formed, may readily and conveniently be adjusted by means of the studs 63 and the apertures 65.

Pneumatic means are preferably provided 100 for actuating the forming angles 58 and consists of an air cylinder 66 having a piston 67 reciprocally mounted therein. The piston rod 68 of the piston 67 has a cross head 69 secured to the upper end thereof which cross head is vertically slidable between vertical 105 guides 71 which preferably have their upper ends secured to the T-shaped jaw 15 of the machine frame and their lower ends suitably secured to the floor by such means as the angle bars 72. Connecting links 73 operatively connect the cross head 69 with the supporting plates 59 of the forming angles 58 so that when the piston is actuated, the forming angles 58 may be simultaneously 110 actuated to bend the wire mesh as shown in Figures 7, 8 and 9. The cylinder 66 is provided with the usual air intake 74 and the exhaust 75, and is provided with a suitable operating or control mechanism, not shown 115 in the drawings.

The material used in the formation of stirrups such as shown in Figure 11, preferably consists of a woven wire mesh comprising a plurality of relatively heavy wires or runners 70 which are held in substantially spaced parallel relation by means of a plurality of relatively finer wires 76 which are arranged at right angles thereto and are usually secured to the heavier wires or runners 70 by such means as welding. In bend- 120 125 130

ing the stirrup, the wire mesh is first cut into rectangular pieces, the size of which is determined by the size of the stirrup desired. A portion of the wire mesh is then inserted 5 between the forming plate 21 and the T-shaped fixed jaw 15 so that the ends of the wires 70 will outwardly project from beneath the forming plate 21, a distance sufficient to form the hooks 77 on one side of the stirrup. 10 When the wire mesh has thus been placed upon the supporting plate 15 the operator will exert a pull upon the operating lever 48 which will cause the eccentric or cam 42 to be rotated with the result that the movable jaw and forming plate will be downwardly forced against the wire mesh against the tension of the springs 41. The clamping member 51 at the opposite end of the jaw will then be upwardly moved from the position 15 shown in Figure 1 to that shown in Figure 2 after which the operator will downwardly rotate the clamping screw 57 in the block 56, thereby causing the clamping block 53 to engage the jaw 19 and thus downwardly force it against the wire mesh. After the wire mesh has thus been securely clamped against the fixed jaw 15 air will be introduced in the lower portion of the cylinder 66 which will upwardly move the piston and therefore 20 the cross head 69. In the initial bending of the wire mesh to form a stirrup, one of the connecting links 73 is preferably disengaged from its complementary plate 59 so that only one of the forming angles are actuated. Thus it will be seen that as the cross head 69 is upwardly moved by the action of the piston, one of the supporting plates 59 will be oscillated upon its pivots 63 thereby causing the forming angle to be 25 oscillated until the wire mesh is brought into contact with the edge of the forming plate 21 as shown in Figure 7. After the ends of the heavy wires on one side of the piece of wire mesh have thus been upwardly and inwardly bent to form the hooks 77, as 30 shown in Figure 7, the piston will be lowered and the forming angle returned to its normal horizontal position after which the connecting link of this forming angle will 35 be disconnected and the connecting link on the opposite side of the machine will be connected to its complementary plate 59. The wire mesh is then released by upward movement of the forming plate 21 after which the wire mesh is further inserted or thrust 40 through the machine until the opposite ends of the wires 70 will be moved into position for bending as above described. The cross head 69 will then again be upwardly moved 45 by the piston 67, thereby causing the forming angle 58 on the opposite side of the machine to similarly upwardly and inwardly bend the opposite ends of the heavy wires 50 of the wire mesh to form thereon the similar hooked ends 77. After each side of the wire 55

mesh has thus been upwardly and inwardly bent to form the hooked ends 77, the forming plate 21 will be upwardly moved to release the wire mesh and the clamping member 51 will also be moved from the position 60 shown in Figure 2 to that shown in Figure 1, after which the wire mesh will be removed from the machine by longitudinally outwardly sliding it from between the forming plate 21 and the T-shaped fixed jaw 15 at the operator's end of the machine. It will then be inverted and again placed between the forming plate 21 and the fixed jaw 15 after which it will again be securely 65 clamped therebetween for the final operation of forming the U-shaped stirrup. Both of the connecting links 73 will then be connected to their complementary plates 59 after which they will simultaneously be actuated by upward movement of the cross 70 head, thereby upwardly bending the two sides of the wire mesh to the position shown in Figure 9, and thus completing the final operation of forming the stirrup. When the stirrup is removed from the machine, it 75 will be in the form shown in Figure 11.

From the foregoing therefore, it will readily be seen that by the use of this novel bending machine, stirrups of various sizes and shapes may be formed in a minimum 80 amount of time, thereby providing a practical device adapted for use in the formation of woven wire or wire stirrups such as are commonly used in the construction of concrete buildings. In Figure 12, there is 85 shown a detail sectional view of a portion of a concrete floor and its supporting beams to indicate how the stirrups are preferably used in the construction of a building. As here shown, it will be seen that the hooked 90 ends 77 of the stirrup are adapted to engage the upper corners of the concrete mold so as to support the stirrup in its proper 95 position within the mold. The usual longitudinal reinforcing bars 78 may also be 100 supported by the stirrups as shown in this 105 figure.

In the drawings, and in the above description, we have referred to the machine as being used to bend U-shaped stirrups for 110 building purposes but it is to be understood that if desired it may also be used to bend sheet metal to be used for troughs or gutters, etc. The machine is also shown as being constructed of structural steel, but obviously, if desired, the frame thereof may be cast and also various changes and modifications may be made in the general construction thereof without departing from the invention. 115

We claim as our invention:

1. A machine of the class described comprising work-clamping jaws, upper and lower, bending aprons pivoted one at each side of and adjacent said jaws adapted when 120

rocked to perform bending operations upon work clampingly held between and projecting laterally from the jaws, a cylinder centrally below the lower jaw and having a vertical piston rod, and links co-pivotaly attached to the rod diverging upwardly and pivotally connecting with respective aprons.

2. A machine of the class described comprising upper and lower jaws, the upper 10 movable, a former plate demountably carried by the upper jaw means for moving the upper jaw to and from clamping position, said former plate having beveled edges L-shaped aprons pivoted on opposite sides of 15 the plate and having depending power arms, a centrally disposed cylinder and piston rod therefor, and connections diverging from and co-pivotaly attached to the rod and connecting with the power arms for applying 20 power for swaying the arms outwardly in opposite directions.

3. A machine of the class described comprising a fixed jaw, a movable jaw guidingly supported at one end only for automatic retraction, means at the guided end of said movable jaw for forcing it toward said fixed jaw, and a swingable clamp device at the other end of said movable jaw for holding it in clamping relation to said fixed jaw, and a lever positioned near said clamp device and operatively connected with the mechanism at the other end of said jaw, whereby the operator stationed at one end of said jaws can control the movement of both ends of said movable jaw.

4. A machine of the class described comprising a lower fixed jaw and an upper movable jaw guidingly supported at one end only, a cam mechanism at the guided end 40 of said movable jaw for forcing it toward the other, a lever at the other end of said jaws operatively connected with said cam mechanism and means adjacent said lever for drawing together the ends of said jaws remote from said cam mechanism.

5. A machine of the class described comprising two elongated relatively narrow jaws, upper and lower, respectively movable and stationary, a counter-balance for the 50 movable jaw, means at one end only of the upper jaw for guidingly forcing it toward the lower jaw, a lever at the opposite ends of the jaws connecting with and actuating said forcing means, and adjustable means adjacent the lever for forcing that end of the upper jaw toward the lower jaw.

6. A device of the class described comprising a horizontal elongated fixed jaw as a work-rest, a movable jaw thereabove guidingly mounted by and at one terminal for vertical clamp reciprocation, and having a demountable former plate thereon as a work clamp of greater width than and extending laterally at each side of the jaws, manually

operable cam means co-operating at the 65 guided end to forcibly advance the movable jaw, said means operable from the opposite ends of the jaws, manually operable clamping means swingable to engage, guide and forcibly advance the movable jaw, terminal 70 plates having rows of openings symmetricaly arranged at opposite sides of the lower jaw substantially at the level of the working face thereof, and bending aprons having pivots for swingingly attaching the same, 75 said pivots traversing corresponding alined pairs of openings of the plates and positioned for bending co-operation with work engaged between the former plate and lower jaw, and means for forcibly operating the 80 aprons.

7. A device of the class described having a horizontal fixed jaw as a work-rest and an elongated movable jaw guidingly mounted at one terminal only for reciprocation relative to the fixed jaw and having a former plate extending laterally beyond the jaws, counter-balance and tension means acting to retract the movable jaw, cam means co-operating at the guided end to forcibly advance the movable jaw, means at the opposite ends of the jaws respectively for actuating the cam means and for engaging, guiding and forcibly advancing the movable 90 jaw, and L-shaped bending aprons pivotally attached and adapted for pivotal adjustment toward and away from the jaws at opposite sides, and adapted to engage work at opposite sides when held between the former plate and lower jaw, and centrally disposed 100 power means below the jaws for applying power to the aprons outwardly in opposite directions.

8. A machine of the class described comprising work-clamping jaws, upper and lower, a forming plate between said jaws extending laterally therebeyond, having opposite edges beveled in correspondence to the bending angle desired, and between which plate and lower jaw, work of greater width than the plate is adapted to be inserted and held, bending aprons respectively cooperable with opposite sides of the work, adapted to be limited in their bending movement by the edges of said forming plate, and power-controlled links connected with the bending aprons for simultaneously or separately obtaining bending motions of the aprons.

9. A machine of the class described, comprising work-clamping jaws, bending aprons pivoted, one at each side of said jaws, a forming plate held between the jaws, between which plate and one of the jaws the work is clamped, and power-controlled links detachably connected with the aprons for operating the same simultaneously or singly to bend the work inwardly around and above the forming plate at an angle determined by

its edges, said plate projectingly disposed and formed to limit and determine the degree of bending movement of said aprons.

10. A machine of the class described comprising clamping jaws, upper and lower, movable and stationary, a former plate secured to the movable jaw and projecting laterally at both sides beyond the jaws, between which plate and lower jaw a piece of metal mesh to be folded is placed, a pair of angle iron members having flanges adapted to normally engage and support the mesh

laterally of the jaws and adapted to engage the mesh, bending the same inwardly and over the former plate in upwardly convergent relation, said members in a subsequent operation being adapted to bend the mesh simultaneously from opposite sides. 15

In witness whereof, we have hereunto set our hands this 21st day of March, 1925

JAMES O. GROFF.
